UNITED STATES PATENT OFFICE.

WILLIAM J. LAUSTERER, OF JAMESTOWN, NEW YORK, ASSIGNOR TO EMPIRE VOTING MACHINE COMPANY, OF JAMESTOWN, NEW YORK, A CORPORATION OF NEW YORK.

INTERLOCK FOR CUMULATIVE VOTING ON VOTING-MACHINES.

1,137,766.

Specification of Letters Patent.

Patented May 4, 1915.

Application filed October 14, 1913. Serial No. 795,054.

To all whom it may concern:

Be it known that I, WILLIAM J. LAUSTERER, a citizen of the United States, residing at Jamestown, in the county of Chautauqua 5 and State of New York, have invented certain new and useful Improvements in Interlock for Cumulative Voting on Voting-Machines, of which the following is a specification.

10 The object of this invention is to provide an interlocking device by which office lines of voting devices may be interlocked to provide cumulative voting for assemblymen as they are voted for in the State of Illinois, in 15 which case each voter is entitled to cast three votes to give all of them for one candidate or $1\frac{1}{2}$ votes for each two candidates or two votes for one candidate and one for another or one vote for each of three different candidates as he may desire.

This and other objects of the invention will be fully illustrated in the drawings, described in the specification and pointed out in the claims at the end thereof.

25 In the accompanying drawings, Figure 1 is a rear elevation of my improved cumulative interlock. Fig. 2 is a rear elevation of the cumulative interlock in which one of the groups of keys has been voted. Fig. 3 30 is a vertical section through the machine on the line 3^x—3^x in Fig. 1 showing the cumulative interlock in engagement with the interlocking straps of the voting devices. Fig. 4 is a vertical section through the machine 35 showing the cumulative interlock out of engagement with the interlocking straps of the voting devices. Fig. 5 is a vertical section through the machine showing the cumulative interlock operated by the interlocking straps of the voting devices. Figs. 40 4 and 5 are taken on the section line 3^x—3^x in Fig. 1, the parts being in different positions. Fig. 6 is a perspective detail view of the interlocking devices on the cumulative 45 lockout. Fig. 7 is a view of the keyboard with the assembly ticket arranged thereon for cumulative voting. Fig. 8 is a plan view of the interlocking channel arranged for the cumulative voting in the assembly 50 group. Fig. 9 is an end view of the frame of the cumulative device partly broken away.

In the accompanying drawings, like reference numerals indicate like parts.

Reference numeral 1 indicates the casing 55 of the voting machine, having ballot indica-

tors thereon such as is shown in Fig. 7. As shown in said figure the keys belonging to the candidates for members of the Illinois Assembly are arranged in twelve office lines. It will be observed in this arrangement that 60 the name of each candidate occurs four times on the machine and that the names of the candidates are divided in two groups. In one group, comprising three office lines, the candidate's name occurs but once and the 65 ballot label indicates that each key voted for such candidate in that group will count as $1\frac{1}{2}$ votes. In the other group, comprising nine office lines, the candidate's name occurs three times and each key voted for such candidate will in that group count one vote. 70

If any one party nominates three candidates, then twelve office lines must be devoted to the whole office but if no party nominates more than two candidates, then 75 but eight office lines need be given to the office, which office will be divided in groups of two office lines and six office lines and if each party nominates but one candidate then but four or five office lines need be given to 80 the office, these office lines being divided into a group of one or two office lines and a group of three office lines. Voting devices on the larger group in each case will count one vote each and the voting devices on the smaller 85 group in each case will count $1\frac{1}{2}$ votes each. On the larger group in each case, the machine must be so adjusted that three keys can be voted therein and in the smaller group in each case, the machine must be so 90 adjusted that two keys can be voted therein and no more. It is usually desirable that the smaller group should not be made smaller than two office lines. The details of the mechanical construction of keys and 95 the regular interlocking devices have been fully explained in the patent to Frank Keiper, 1,031,184, this invention being confined solely to the cumulative interlock which is supplemental to the regular interlocking devices described therein. 100

In the machine are mounted the interlocking straps 2, having the interlocking wedges 3 thereon. The wedges engage with the rollers 4, mounted on the interlocking channel 5 and held in place by the gripping pins 6. On the interlocking straps are formed the shoulders 7 with which the cumulative interlock can engage. 105

In the bottom of the machine is fastened 110

an angle iron 8 to which is fastened in a suitable manner a plate 9 which plate has openings 10 therein at suitable intervals, preferably the same distance between centers 5 as the distance between centers of office lines.

The cumulative device is built upon a plate 11, having brackets 12 on one side thereof which brackets are adapted to make contact with the bottom of the machine. 10 The plate 11 also has the cleats 13 fastened therein which cleats are adapted to engage with the plate 9 by which the cumulative interlocking device may be adjustably fastened in place.

15 On the opposite side of plate 11 are fastened the flanges 14, 15, 16 and 17, these flanges being substantially alike except that the angles of flanges 14 and 16 by which they are fastened to the plate 11 are turned to the right and the angles of flanges 15 and 17 are turned to the left. On the outer flanges 14 and 17 are pivotally mounted the hooks 18 and 19, adapted to engage with the openings 10 in the plate 9. These hooks are 20 moved forward by the eccentrics 20 by which they are held in locked position.

The plate 9 extends the whole length of the machine and by means of the attachments just described, the cumulative interlocking device may be fastened in any part 30 of the machine so that it will engage with the interlocking straps of any desired set of office lines. Mounted in the flanges 14 and 15 is the shaft 20 and in the flanges 16 and 35 17 is mounted the shaft 21. Both shafts 20 and 21 are preferably angular in cross section. Mounted on the shaft 20 are the arms 22, 23 and 24. Through the outer ends of these arms pass the rod 25. On this rod are 40 pivoted the wings or blades 26, 27 and 28. On the lower ends of these blades are the guards 29, 30, 31, 32, 33 and 34. These blades are pivotally mounted on the rod 25 and can be set either in the position shown 45 in Fig. 3 or that shown in Fig. 4. Fastened to each of these blades is a stud 35 to which is pivotally connected a link 36 having recesses 37 and 38 therein.

Mounted in the arms 22, 23 and 24, is the 50 rod 39, on which the links 36 can rest and engage therewith with either of the recesses 37 or 38, by which engagement they will be held against endwise movement, thus holding the wings 26, 27 and 28 in engaged 55 position as shown in Fig. 3 or disengaged position as shown in Fig. 4. The outer end of each link 36 is extended downwardly as shown at 60 in Fig. 4 and has pivoted thereto to the locking dog 40, which dog has a shoulder 60 41 thereon adapted to engage under the rod 39. By means of this link and dog the wings 26, 27 and 28 can be locked in either position shown in Figs. 3 and 4.

The shoulders 7 on the interlocking straps 65 will make engagement with the wings 26,

27 and 28 and raise them from the position shown in Fig. 3 to that shown in Fig. 5, carrying with them the pivoted frame which supports them. The wings 26, 27 and 28 are each long enough to engage with the interlocking straps of three office lines and the movement of any one of the plates to the position shown in Fig. 5 will carry with it all of the other plates whether they are in extended or retracted position.

70 The shaft 21, arms 22, 23 and 24, bar 25, with the wings 26, 27 and 28 thereon and the rod 39, etc., all constitute a frame which moves as a unit.

The arm 23 is perforated as shown at 45. 80 Pivotally mounted on the plate 11 is the interlocking dog 46 which has a finger 47 that engages with the recess 45 in the arm 23. On the plate 11 is the stud 48 by which the upward swing of the dog is limited.

85 On the right hand end of the plate 11, as shown in Figs. 1 and 2, is a smaller frame made up of the wings 49, 50 and 51, each of which wings is adapted to engage a single office line of interlocking straps, the wings 90 being otherwise shaped and mounted exactly like the larger wings 26, 27 and 28. They are also adjustable forward and back in the same manner and locked in the same manner.

95 Pivotally mounted on the plate 11 is the interlocking dog 52, which dog has a hook 53, engaging with the arm 54 which is part of the frame carrying the small wings and which arm is perforated in the same way as 100 is the arm 23. The dogs 46 and 52 extend toward each other and have at their ends the inclined surface shown in Figs. 1, 2 and 6.

Pivotally mounted on the plate 11 is the interlocking dog 55, having the stud or a 105 pin 56 thereon which pin extends over the upper edge of the plate 11 and has a washer 67 mounted on the outer end thereof by which washer the dog 55 is guided as it swings forward and back. The pin 56 makes 110 contact with the plate 11 or the inclined surfaces of the dogs 46 and 52. When the left hand frame, as shown in Fig. 2 is lifted the dog 46 swings up and throws the dog 55 to the right at the top. Each of the dogs 115 46 and 52 has a square end with which the stud 56 can make contact when either of the dogs is up, thereby limiting the swinging of the dog 55. When the dog 46 is up, the dog 55 has been moved to the right and is prevented from moving to the left and the dog 52 is thereby held down.

When the dog 52 is raised, the dog 55 swings to the left and holds the dog 46 down. By means of these dogs, it will be seen that only one of the frames can be lifted at a time. The frames are lifted by the voting of keys. These keys are divided into two groups, one of which contains three office lines or less and the other of which contains nine office lines or 120 125 130

less. When the keys are voted in the one group, no keys can be voted in the other group. When the keys are reset in either group, the frame controlling them drops 5 back by gravity permitting the lifting of the other frame and the voting of the keys in the other group. One or more springs 57 are placed on each frame which springs tend to lift the frames and make easier the 10 voting of the keys controlled by the frames. The springs are not strong enough in either case to lift the frame or prevent the return of the frames by gravity.

I claim:

15 1. In an interlocking device, the combination of a support, a plurality of frames mounted to swing on said support, and an interlocking device on said support permitting the swinging operation of either one of 20 said frames, but not both at the same time.

2. In an interlocking device, the combination of a support, a plurality of frames mounted to swing on said support, and a plurality of blades on each of said frames, 25 said blades being adapted to swing forward and back on said frames.

3. In an interlocking device the combination of a support, a plurality of frames mounted to swing on said support, and a 30 plurality of blades on each of said frames, said blades being adapted to swing forward and back on said frames, and means for locking said blades in either their forward or back position.

35 4. In an interlocking device, the combination of a support, two vertically movable frames mounted on said support, blades mounted on each of said frames, said blades being adjustable forward and back thereon, 40 and interlocking devices to prevent the vertical movement of more than one of said frames at a time.

5. In an interlocking device, the combination of a plate, flanges fastened to said 45 plate, and frames pivotally mounted in said flanges, each of said frames having a series of blades mounted thereon and adjustable forward and back thereon.

6. In an interlocking device, the combination of a plate, flanges fastened to said plate, and frames pivotally mounted in said flanges, each of said frames having a series of blades mounted thereon and adjustable forward 50 and back thereon, said blades being in line with each other, each of said blades having 55 guards extending out from the ends thereof.

7. In an interlocking device, the combination of a support, cleats on said support, a stationary bar adapted to be engaged between 60 said cleats and said support, said bar having perforations therein, and dogs on said support adapted to engage with said perforations.

65 8. In an interlocking device, the combination of a support, cleats on said support, a

stationary bar adapted to be engaged between said cleats and said support, said bar having perforations therein, and dogs on said support adapted to engage with said perforations, and means for locking said 70 dogs in engagement with said support.

9. In an interlocking device, the combination of a support, a pair of dogs mounted thereon at the outer ends of said support, their free ends being nearly in contact with 75 each other, and a third dog having a stud thereon mounted to swing over the free ends of said pair of dogs, the upward movement of either of said pair of dogs being adapted to swing the stud over the other dog and 80 prevent the upward movement thereof.

10. In an interlocking device, the combination of a support, a pair of dogs mounted thereon at the outer ends of said support, their free ends being nearly in contact with 85 each other, and a third dog having a stud thereon mounted to swing over the free ends of said pair of dogs, the upward movement of either of said pair of dogs being adapted to swing the stud over the other dog and 90 prevent the upward movement thereof, and a stationary stud over each dog to limit the upward movement thereof.

11. In an interlocking device, the combination of a support, a pair of dogs mounted 95 thereon at the outer ends of said support, their free ends being nearly in contact with each other, and a third dog having a stud thereon mounted to swing over the free ends of said pair of dogs, the upward movement of either of said pair of dogs being adapted to swing the stud over the other dog and prevent the upward movement thereof, and a pair of frames pivotally mounted on said support, one of said dogs 100 being connected to each of said frames whereby the upward movement of both of said frames simultaneously is prevented.

12. In a voting machine, the combination of a series of keys arranged in office 110 lines, an interchangeable interlocking device for said keys, said interlocking device being capable of dividing said keys into two groups with a plurality of office lines in each group, and a supplemental interlocking device 115 for controlling said groups of keys to permit the voting of keys in either of said groups and prevent the voting of keys in both of said groups simultaneously.

13. In a voting machine, the combination of a series of keys arranged in office lines, an interchangeable interlocking device for said keys, said interlocking device being capable of dividing said keys into two groups with a plurality of office lines in each group, and a supplemental interlocking device 120 for controlling said groups of keys to permit the voting of keys in either of said groups and prevent the voting of keys in both of said groups simultaneously, said 125

supplemental device being capable of controlling a variable number of office lines in each group.

14. In a voting machine, the combination of a series of keys arranged in office lines, an interchangeable interlocking device for said keys, said interlocking device being capable of dividing said keys into two groups with a plurality of office lines in each 10 group, and a supplemental interlocking device for controlling said groups of keys to permit the voting of keys in either of said groups and prevent the voting of keys in both of said groups simultaneously, said 15 supplemental device having adjustable devices thereon capable of engaging and controlling a variable number of office lines in each group.

15. In a voting machine, the combination of a series of keys arranged in office lines, an interchangeable interlocking device for said keys, said interlocking device being capable of dividing said keys into two groups with a plurality of office lines in each 20 group, and a supplemental interlocking device for controlling said groups of keys to permit the voting of keys in either of said groups and prevent the voting of keys in both of said groups simultaneously, said 25 supplemental device having adjustable devices thereon capable of engaging and controlling a variable number of office lines in each group, and means for locking said adjustable devices in or out of their engaging 30 position.

16. In an interlocking device comprising a plate, means for holding said plate in an upright position, two pairs of flanges on said plate, a square shaft mounted to rock 40 in each pair of flanges, a series of arms on each of said square shafts, a bar mounted on the outer ends of each of said square shafts, and blades pivotally mounted on each 45 of said bars.

17. In an interlocking device comprising a plate, means for holding said plate in an

upright position, two pairs of flanges on said plate, a square shaft mounted to rock in each pair of flanges, a series of arms on each of said square shafts, a bar mounted 50 on the outer ends of each of said square shafts, blades pivotally mounted on each of said bars, and guards on each end of each of said plates.

18. In an interlocking device comprising 55 a plate, means for holding said plate in an upright position, two pairs of flanges on said plate, a square shaft mounted to rock in each pair of flanges, a series of arms on each of said square shafts, a bar mounted 60 on the outer ends of the arms on each of said square shafts, blades pivotally mounted on each of said bars, links fastened to each of said blades, and an intermediate bar supported in each set of arms, said links having 65 recesses therein with which they are adapted to engage with said bar and hold said blades in either of a plurality of positions.

19. In an interlocking device comprising a plate, means for holding said plate in an 70 upright position, two pairs of flanges on said plate, a square shaft mounted to rock in each pair of flanges, a series of arms on each of said square shafts, a bar mounted on the outer ends of the arms on each of said square 75 shafts, blades pivotally mounted on each of said bars, links fastened to each of said blades, an intermediate bar supported in each set of arms, said links having recesses therein with which they are adapted to engage 80 with said intermediate bar and hold said blades in either of a plurality of positions. 85

In testimony whereof I affix my signature in presence of two witnesses.

WILLIAM J. LAUSTERER.
